Attys.

UNITED STATES PATENT OFFICE.

FREDERICK W. SPERR, JR., OF PITTSBURGH, PENNSYLVANIA, ASSIGNOR TO THE KOPPERS COMPANY, OF PITTSBURGH, PENNSYLVANIA, A CORPORATION OF PENNSYLVANIA.

METHOD OF AND APPARATUS FOR TESTING MATERIALS.

Original application filed July 24, 1918, Serial No. 246,599. Divided and this application filed August 12, 1922. Serial No. 581,417.

To all whom it may concern:

Be it known that I, FREDERICK W. SPERR, Jr., a citizen of the United States, residing at Pittsburgh, in the county of Allegheny and State of Pennsylvania, formerly residing at Oakmont, in the same county and State, have invented a new and useful Improvement in a Method of and Apparatus for Testing Materials, of which the following is a full, clear, and exact description, reference being had to the accompanying drawings, forming part of this specification, in which:

Figures I and II are diagrammatic views embodying my invention, and

Figure III is a similar view showing a modification.

This is a division of my co-pending application, Serial No. 246,599, filed July 24, 1918.

This invention relates to a method for testing the behavior of substances on heating and also to apparatus that I have developed to carry out this method. The method and apparatus have been more particularly designed for the testing of coal, the behavior of which at high temperatures is of great importance in the arts; and in the ensuing description I have usually referred to coal as the substance to be tested, but it is to be understood that the method may also be applied to a wide variety of other materials. My method offers a means of determining all or any of the following important characteristics of a material.

1. The rate of volume change under progressive heating and the total volume change after heating.

2. The pressure developed by the material when heated in a confined space.

3. The character of the product formed after subjecting the material to progressive heating at various rates.

4. The nature and quality of any byproduct formed by progressive heating of the material.

It may readily be seen that such information is of importance in relation to a wide range of material.

5. In the case of coal, it is often desirable to determine, upon a small scale, the quality of the residue left after heating the coal to a given temperature. This is of particular

interest in connection with the investigation of coking coals, since the quality of the coke made from such coal is of very great industrial importance. Moreover, certain coals expand during the coking process, while others contract. In the case of coals which expand, it is necessary to be able to determine the amount of pressure developed when the coals are coked in a confined space. The behavior of coal upon heating, the nature of the coke and byproducts, the amount of expansion or contraction, and the pressure developed during coking are profoundly affected by such factors as the rate of heating, total time of heating and temperature.

In the industrial coking of coal, it has been proven by a number of different investigators that the heat penetration proceeds in such a way that the zone of high temperature in which the coking has taken place is always marked by rather sharply defined limits. When the coking has advanced, say, four inches from the wall of the oven, the temperature at that point will be quite high—possibly over 800° C., while two inches further in toward the center of the oven the temperature will be several hundred degrees lower. Some of the most important features of the coking process appear to be related to this manner of heat penetration, and if satisfactory results on small scale tests are expected, this condition must be imitated as closely as possible. This is what is accomplished by my method. One form of apparatus that I have used is shown in diagrammatic form in Figure I.

In the tube A is placed a sample of coal, occupying the space B. The coal is preferably pulverized to approximately 20 mesh size, although other degrees of fineness may be used. A weighed quantity of coal is always used. The sample is held in place by the plugs C and C'. Plug C is preferably fixed so as to prevent expansion of the coal toward the cold end of the tube while plug C' is movable. Plug C, however, might be made removable to facilitate the insertion and removal of the test material. The tube A is preferably made of fused quartz although other refractory material, such as glass, porcelain, or iron may be used. Quartz is preferred on account of its refractory quality and low coefficient of expansion.

The tube A is supported at one end by the support J, while the other end rests upon the furnace D. The source of heating is the electric furnace D, which fits over the tube 5 and has a tubular heating chamber, the length of which is preferably somewhat greater than the length of the sample and than the length of the section B occupied by the sample. The furnace D may also be 10 heated by gas, although an electric furnace is preferable. The furnace D is mounted on a carriage E, which runs over the track F. A pointer G attached to the carriage indicates upon the scale H the exact position 15 of the end of the heating chamber of the furnace with respect to the end of the section occupied by the coal sample.

When testing coal, I weigh out such a sample that the space B is approximately 9 20 inches long, corresponding to the distance from the wall to the center of the usual by-product coke oven.

In its simplest form, the test consists in 25 moving the furnace D slowly in the direction of the arrow I until the furnace covers all of the section B. The tube is then removed from its support and from the furnace and the residue in section B taken out for examination. In the case of a good coking 30 coal, this residue consists of a heat cylinder of coke. The total expansion or contraction that has taken place in the coking operation may be obtained by measuring the length of this cylinder. Various rates of coking may 35 be imitated by moving the furnace faster or slower, always timing the progress of heating with reference to the position of the pointer G on the scale H. Various temperatures of coking may be tested by varying the 40 temperature of the furnace D.

The laws of physics show that the time required for the flow of heat through a solid mass, one face of which is being heated, or in other words, the time required to effect a 45 predetermined increase of temperature, is proportional to the square of the distance from the heated face. Certain investigations show that this law is approximately applicable to the progress of heating in the 50 coking of coal. In order to make the small scale tests comparable with actual practice, it is desirable to conform to this law of heating which may be readily done with my apparatus. I have found it preferable to advance the furnace over the section B at a 55 rate in which the distance traveled is a function of the square root of the time. For example, suppose the total section 9 inches long is to be heated in four hours, then according to the square root rule, one-half of the 60 9 inches would be traversed in the first hour. $\sqrt{1/2 \times 9''}$ in the first two hours, the $\sqrt{3/4 \times 9''}$ in the first three hours, etc. I have adopted the practice of making heating 65 curves corresponding to each rate of heating

and these are followed by moving the apparatus by hand, but an apparatus may also be used in which the motion is made automatic by clock work or otherwise.

In the simplest method of testing, it is 70 not absolutely essential to the principle of the method to use the plugs C and C', although better results are obtained by using these plugs.

When it is desired to determine the 75 expansion or contraction of the sample at various stages of heating, a light rod K is placed with one end in contact with the removable plug C', the other end operating against a pointer L suspended in such a way 80 as to indicate the movements of the plug on the scale M. The apparatus may be arranged so that the weight of the pointer is sufficient to keep the rod K in contact with the plug through any contraction that may take 85 place, but other means may be used to this end. The rod K moves upon bearings placed on the support N.

In case it is desired to determine the pressure exerted at various stages of heating, 90 the apparatus shown in Figure II is used. Here, for sake of simplicity, the tube is shown without supports or furnace. The rod O which is preferably made of silica and is stronger than the rod K, shown in Figure 95 I, is held firmly in contact with the plug C' and rests upon the support N. By a suitable arrangement of levers P P, the pressure developed is transmitted to the pan of a balance Q which is of a type requiring a very 100 small degree of movement to indicate a given pressure. Balances may be obtained in which the required movement is less than $\frac{1}{8}$ inch. For this purpose, I prefer to use a platform scale, such for instance, as that defined in the Bureau of Standards Bulletin, issued May 1915, entitled "Tolerances and specifications for weights and measures and weighing and measuring devices." The specific form of scale adapted for this purpose 105 is one manufactured by the Toledo Scale Company, of Toledo, Ohio, and known as "Scale No. 641."

While I have illustrated in Figures I and II a form of my invention in which the tube 115 is stationary and the furnace stationary, I may use a stationary furnace and move the tube therethrough. This modification of my invention is shown in Figure III, in which the corresponding parts have been given the 120 same reference numerals as in Figures I and II, but with the affix "M" applied thereto. In this figure, I have also indicated more mechanically the character of the indicator which may be employed in indicating the 125 extent of the expansion or contraction of the test sample. It consists of a pointer L', adapted to move over a scale M', and carried by a bell crank lever which is acted upon by the rod attached to the plug C. If 130

it is desired simply to ascertain the character of the product resulting from heating, both plugs C C' may be held in fixed relation to each other. Various other changes 5 can be made in the details of construction and arrangement of the parts without departing from the spirit and scope of my invention as defined in the claims.

The words "tube" and "tubular" as used 10 herein and in the claims with respect to the container employed are to be broadly construed as covering any container of suitable character in which a test sample can be confined and treated as described.

15 I claim:

1. Apparatus for testing materials, comprising a refractory container and a heating furnace, the furnace and container being progressively movable relatively to each 20 other, together with means actuated by the pressure generated in the container for indicating such pressure.

2. Apparatus for testing the pressure developed by heating substances, comprising 25 a refractory tube adapted to contain a sample of the substance, a movable plug fitting against the end of the sample, apparatus connected with said plug and operating on the principle of a balance to indicate or 30 record the pressure developed, and a furnace

adapted to heat the tube, said tube and furnace being so mounted as to permit relative motion so that the sample may be heated progressively from one end to the other.

35

3. Apparatus for testing the pressure developed by heating substances, comprising a refractory tube, adapted to contain a sample of the substance, plugs fitting against the ends of the sample, the plug nearest the 40 source of heat being movable, and the opposite plug being fixed, and an apparatus operating on the principle of a balance connected with the movable plug and adapted to register the changes occurring in the sample by heating it, the tube and furnace being so mounted as to permit of relative motion so that the sample may be heated progressively from one end to the other.

45

4. The herein described method of testing the behavior of substances on heating, consisting in enclosing a sample of the substance in a refractory container and applying heat progressively from one end of the sample to the other by moving the two relatively to a heated zone, and measuring the 50 pressure generated.

55

In testimony whereof I have hereunto set my hand.

FREDERICK W. SPERR, JR.
